(57) CLAIM

The ornamental design for a baby carrier substantially as shown and described.

DESCRIPTION

FIG. 1 is a perspective view of a baby carrier showing the new design;

FIG. 2 is a front view of a baby carrier showing the new design;

FIG. 3 is a rear view of a baby carrier showing the new design;

FIG. 4 is a left side view of a baby carrier showing the new design;

FIG. 5 is a right view of a baby carrier showing the new design;

FIG. 6 is a top view of a baby carrier showing the new design;

FIG. 7 is a bottom view of a baby carrier showing the new design;

FIG. 8 is a perspective view of the baby carrier showing the new design with the hood deployed;

FIG. 9 is a front view of the baby carrier showing the new design with the hood deployed;

FIG. 10 is a rear view of the baby carrier showing the new design with the hood deployed;

FIG. 11 is a left side view of the baby carrier showing the new design with the hood deployed;

FIG. 12 is a right side view of view of the baby carrier showing the new design with the hood deployed;

FIG. 13 is a top view of the baby carrier showing the new design with the hood deployed; and,

FIG. 14 is a bottom view of the baby carrier showing the new design with the hood deployed.

The dash-dot-dash lines show claimed stitching on the baby carrier. The dashed lines indicate features that form no part of the claimed design.

1 Claim, 14 Drawing Sheets

Related U.S. Application Data

continuation of application No. 29/715,276, filed on Nov. 29, 2019, now Pat. No. Des. 912,394, which is a continuation of application No. 29/671,656, filed on Nov. 29, 2018, now Pat. No. Des. 876,824, which is a continuation of application No. 29/608,852, filed on Jun. 26, 2017, now Pat. No. Des. 835,902.
